UNITED STATES PATENT OFFICE.

ARTHUR G. GUENTHER, OF CHICAGO, ILLINOIS, ASSIGNOR TO J. S. McCHESNEY & CO., OF CHICAGO, ILLINOIS, A CORPORATION OF ILLINOIS.

WIRE-TYING MACHINE.

1,324,590.

Specification of Letters Patent.

Patented Dec. 9, 1919.

Application filed October 3, 1917. Serial No. 194,442.

To all whom it may concern:

Be it known that I, ARTHUR G. GUENTHER, citizen of the United States, residing at Chicago, in the county of Cook and State of Illinois, have invented certain new and useful Improvements in Wire-Tying Machines; and I do hereby declare the following to be a full, clear, and exact description of the invention, such as will enable others skilled 5 in the art to which it appertains to make and use the same.

My invention relates to wire-tying machines, and more particularly to machines for banding boxes or other objects with wire. 15 In its general aspects, the objects of my invention are to provide a simple, compact and positively operating mechanism for enabling boxes or the like to be rapidly banded with wire fed from a continuous coil or 20 reel; for enabling the tensioning of the wire to be effected with a uniform and predetermined degree of tautness; and for automatically moving the object during the tensioning of the wire, so that the wire will be 25 tightened with substantial uniformity over the several edges of the object. Furthermore, my invention aims to provide a simple and effective means for speedily tensioning the wire by a single and continuous pull; 30 for automatically adjusting the extent to which the wire is retracted, so as to afford the desired tensioning; for enabling the tensioning to be done by power means, and for preventing a possible damaging of the 35 parts by an excessive movement thereof in case of a breaking of the wire. So also, my invention aims to provide simple and effective means for automatically returning the wire-pulling clamp to its initial position.

40 after the loop-tightening, wire fastening and wire severing operations have been completed for each loop or band; for automatically opening this clamp when returned to its initial position; for easily starting the 45 loop tightening, twisting and severing mechanism in operation, and for limiting the amount of the intertwisting of the loop portions to a predetermined extent; also to provide simple means for lifting the banded 50 or wire-bound object clear of all operative parts of the mechanism, and to provide safety means for guarding against a premature actuating of this lifting mechanism. Further and to some extent more detailed 55 objects will appear from the following speci-

fication and from the accompanying drawings, in which drawings—

Figure 1 is a fragmentary plan view of a machine embodying my invention.

Fig. 2 is a fragmentary side elevation of 60 the same, with some portions of the supporting frame omitted to avoid the concealing of important parts of the mechanism.

Fig. 3 is an enlarged horizontal section 65 through a portion of the stripping mechanism, taken along the line 3—3 of Fig. 2.

Fig. 4 is a vertical section through portions of the stripping and twisting mechanism, taken along the line 4—4 of Fig. 3.

Fig. 5 is an enlarged vertical section showing 70 portions of the friction drive arrangement and taken along the line 5—5 of Fig. 2.

Fig. 6 is an enlarged vertical section through portions of the clutch and of the clutch-actuating mechanism, taken along the 75 line 6—6 of Fig. 2.

Fig. 7 is an enlarged vertical section showing details of the clutch and the clutch-actuating mechanism.

Fig. 8 is a fragmentary horizontal section 80 taken along the line 8—8 of Fig. 7.

Fig. 9 is a diagrammatic view showing the single-directioned or cumulatively slipping tensioning of the wire by the box banding methods heretofore in use.

Fig. 10 is a similar view indicating the double-directioned or symmetrically balanced tensioning of the wire as accomplished by the machine of my invention.

Fig. 11 is a fragmentary view showing 90 the means for automatically opening the wire-pulling clamp when returned to its initial position.

In many of its general aspects, my invention relates to wire-tying and wire-banding 95 appliances of the type of those shown in applications No. 130941 and 140883, as both filed by John Sherman McChesney of Chicago. These applications disclosed mechanism for tightening a loop of wire disposed 100 around a box or other object, for intertwisting overlapped portions of the wire loop, and for thereafter severing the finished wire loop from the supply of wire. In the cited McChesney applications, the tightening 105 of the loop is accomplished gradually through a step-by-step operation by foot power, thereby requiring an amount of muscular strength and time which I propose to save by substituting mechanical 110

power and a single continuous pull. Moreover, with the McChesney appliances, the tensioning of the wire is all accomplished from one direction as viewed in relation to 5 the object which is being banded, thereby causing decided differences in the extent to which the wire indents the several edges of the object. My invention proposes to provide means for automatically moving the object 10 during the tightening of the loops or band around the same, thus distributing the tensioning as uniformly as if the loop had been simultaneously tightened in two opposite directions, and thereby enabling wire bands of this general class to be used even 15 on objects having relatively delicate surface portions. However, while I have referred to my invention as implying an improvement upon the disclosure of the said McChesney applications, I do not wish to be limited to embodiments based upon the said disclosures; neither do I wish to be limited 20 to the use of wire in the round form as illustrated, as my appliance should function 25 equally well with wires or bands of other sections and should be equally suitable for use with other objects than the rectangularly sectioned box which I have illustrated in explaining the operation of one particular embodiment.

In the embodiment of the drawings, the appliance of my invention includes a table 1 mounted on a frame 2, some parts of which supporting frame have been omitted to 35 avoid concealing important elements of the mechanism. Mounted on the upper face of the table are plates 3 and 4 having aligned slots extending longitudinally of the table and adapted to be entered by portions of the 40 wire. These plates are equipped with spring pressed plungers 5, one of which is normally sufficient in the plate 4 while the plate 3 is desirably equipped with a number of such plungers or spring latches so as to accommodate 45 considerable variations in the sizes of the packages which are to be banded. The plate 1 has a substantially central opening exposing a portion of the wire-twisting pinion 6, and also exposing the tips 7 of a 50 vertically movable stripper, which stripper has tips normally flush with the surface of the table and which may be raised to lift the banded package clear of the wire twisting mechanism, the latter mechanism being 55 here shown in the same form as in the heretofore mentioned application of John Sherman McChesney. As parts of this mechanism, the table 1 carries grippers 8 arranged for clamping certain portions of the 60 wire loop, and also carries a pair of stops against which the package abuts when in position for banding. Each of these stops desirably comprising a plate 9 rigid upon the table 1 and having an extension 65 mounted thereon and adjustable in position

so as to adapt itself to varying sizes of the packages with which the machine is to be used. Each of these extensions 10 has pivoted upon it a stop arm 11 which is normally swung outward, or into the position shown in Fig. 1, by a spring 12.

Mounted also upon the table 1 and desirably extending between the said plates 9, is a slide 13 carrying opposed gripper jaws 14, which jaws coöperate with cam formations on the slide for causing the jaws to be pressed toward each other when they are moved toward the right with the machine viewed as in Fig. 1. Each of these jaws desirably has its tip also equipped with 75 a cam formation adapted to engage co-operating formations on the table 1 when the jaw is pressed to its extreme forward position by a spring 15 (as shown more in detail in Fig. 11), thereby opening the jaws 80 automatically when in their initial position or the position nearest to the package which is to be banded. The slide carrying the said jaws is fastened to one end of a flexible member, desirably in the form of a chain 16, 85 which member passes over a guide pulley 17 mounted on a slide 18, the latter being normally forced away from the wire twisting portion of the machine by a spring 19. The other end of the chain 16 is fastened to 90 a drum 20 and adapted to be wrapped around this drum when the latter is rotated. The drum 20 is mounted on a stationary shaft 21 and is normally held from rotation about this shaft by a spring 22 connecting 100 the two, thereby holding the drum in a position in which a lug 23 upon the same engages a bar 54 forming part of the frame of the machine. The drum 20 has upon one of its faces an incomplete friction ring 24, desirably beveled in section and adapted to be engaged by a friction wheel 25 on a shaft 26 connected through a universal joint 27 with the shaft of a continuously running motor 58. The shaft portion 26 is partly supported by a bell crank lever 28 which is pivoted to a portion of the frame of the machine, and which lever may be moved through a link 29 by a treadle 30, so as to 110 press friction wheel 25 against the incomplete annular friction surface 24 on the drum 20. However, the said friction elements are normally held out of engagement by suitable means, such as a spring 31 socketed in a portion of the bell crank 28 and bearing against a part of the frame of the machine as shown in Fig. 5.

The wire-twisting mechanism of the machine desirably includes a pinion 6 so proportioned as to be given the desired number of revolutions by a single rotation of a gear 32 which meshes with this pinion and which is carried by a twister shaft 33. The twister shaft is connected to a continuously rotating wheel 34 by a clutch arranged for 125 130

connecting the two only for a single rotation of the shaft 33. For this purpose I have here shown a clutch body 35 fast upon the shaft 33, on which shaft the wheel 34 is freely rotatable. The clutch body 35 carries a sliding pin 36 having one end adapted to enter a socket in the hub of the wheel 34 and having at its other end a head 37 connected to suitable spring means tending to move the pin 36 into its said latching or connecting position. However, this movement of the pin is normally prevented by the interposing of the end of a latch 38 between the body 35 of the clutch and the said head 37, as shown in Figs. 6 and 7 and in the said McChesney application. The latch 38 is pivoted upon a portion of the frame of the machine and continuously pressed toward its latching position by a spring 39, out of which position it may be moved by the pressure of a trip lever 40, which lever is pivoted on a swinging arm 41 as shown in Figs. 7 and 8. The arm 41 is continuously urged in one direction by a spring 42 connecting the same with a rigid portion of the frame of the machine, thereby normally holding the lever 40 in a position in which the beveled end of the said lever alines with the beveled tip of a rod 43 fastened to the slide 18. Normally, the lever 40 is held in the position of Fig. 7 by a spring 44 interposed between this lever and the swinging arm 41, thus maintaining the outer end of the lever 40 in a position in which it permits the spring 39 to hold the latch 38 operative for disconnecting the shaft 33 from the wheel 34, the latter wheel being continuously driven by the motor 28 through a belt 45. However, when the operating rod 43 is moved toward the left in Figs. 2 and 7, the cam formation of its tip rocks the lever 40, thereby moving the latch 38 out of its operative or interposed position and permitting the clutch pin 36 to connect the wheel 34 with the shaft 33, and thus actuating the wire intertwisting pinion 6. While thus rotating, the clutch body 35 carries a lug 46 upon the same into the path of a lug 47 on the lever 40, thereby swinging the arm 41 into the position shown in dotted lines in Fig. 8, and thus carrying the beveled end of the lever 40 out of the path of the operating rod 43. As soon as this occurs, the spring 44 rocks the lever 40 back to its initial position, thereby enabling the spring 39 to return the pivoted latch 38 to the normal position in which it engages the beveled tip of the projection 37 as the clutch approaches its starting position, and thus releasing the pin 36 from its clutching engagement. In so doing, a portion of the latch 38 is also brought into position for engaging a lug 48 on the clutch body and thereby positively stopping the clutch body and the shaft 33 in a predetermined posi-

tion. Meanwhile, since the beveled end of the rocking lever 40 has been swung to one side of the toe of the operating rod 43 and then snapped upward, this toe will be interposed between the beveled end of the said lever and a stop 49 forming part of the frame of the machine shown in Fig. 8, thereby preventing the spring 42 from swinging the arm 41 and the lever carried by the latter back into its operative position. Consequently, any continued longitudinal forcing of the rod 43 will not actuate the clutch again, as the clutch-actuating mechanism will not again be in operative position until the rod 43 has first been retracted so as to permit the spring 42 to return the arm 41 and the lever 40 to their initial positions. In other words, when the twister shaft 33 has once been rotated, no further rotation of this shaft can occur until the operating rod 43 has first been retracted to its normal position.

To return the slide 13 and the gripper jaws 14 carried by the same to their initial positions, I desirably provide a flexible band 50 also connected to the drum 20, but in the opposite direction from the chain 16, and thus practically coöperating with the chain to form an endless band wrapped partly around the drum and moved by the latter. To move the stripper 7 I desirably provide a link 51 operatively connected to a treadle 52 and adapted to engage the stripper 7 and to lift the latter when the said treadle is depressed. However, an inexperienced or nervous operator might accidentally depress this treadle 52 at a wrong time, hence I preferably provide means for normally holding the link 51 out of operative relation to the stripper 7. Thus, I may guide the link 51 by a pivoted arm 53 as shown in Figs. 3 and 4 and may connect this link also to a rod 54 which is normally pressed toward the right hand end of the machine by a spring 55, but which may be moved against the resistance of the said spring by pressing a knob 56. With the safety provisions thus arranged, a pressing of the treadle 52 will not actuate the stripper unless it has been preceded by a pressing of the knob 56.

In operating the machine as above described, the wire 57 is taken direct from a reel 58, bent into a looped formation and snapped into position as more particularly described in the cited McChesney application heretofore mentioned. That is to say, the supply portion of the wire is snapped under the spring latch 5 located between the swinging jaws 11, then disposed in loop formation and the free end of the wire is snapped under one of the left hand spring latches 5. Next, the overlapping wire loop portions are both inserted in the upwardly open slot of the wire twisting pinion 6, with

the portion leading to the reel uppermost, and the loop portions are clamped by the spring grips 8. Then the portion of the wire leading to the reel is gripped between the 5 wedging jaws 14 and the main treadle 30 is depressed. This depressing of the treadle actuates the friction drive and the chain 16 through the jaws 14 to exert a single and continuous pull on the wire, the free end of 10 which wire is gripped as before stated. The resulting tensioning of the wire around the package 59 tends to draw this object toward the right in Figs. 1 and 2, thereby moving the swinging stops 11 against the 15 pressure of the spring 12 and thus permitting the wire to be slid around the corners of the box partly from one end of the loop and partly from the other end. In other words, instead of having the sliding of the 20 wire increase cumulatively over the successive corners A, B, C and D of the box as in Fig. 9, the box itself slides somewhat toward the right, so that the sliding of the wire is cumulative only as between the corners 25 A and B and the corners C and D respectively as indicated in Fig. 10.

While the chain or flexible element 16 is thus tensioning the wire of the loop, the pull on this chain will also tend to strengthen 30 the latter, as by moving the idle wheel 17 toward the left in Fig. 2. Consequently, this action will tend to move the slide 18 toward the left and such a sliding takes effect as soon as the resulting strain is sufficient to overcome the pressure of the spring 19. Then the continued pull on the chain 16 due to the winding of the latter on the drum 20 will move the slide 18 instead of causing a further tensioning of the wire 35 loop, so that the spring 19 automatically regulates the degree to which the wire loop is tightened. The movement of the slide 18 carries with it the operating rod 43, thus causing the latter to rock the lever 40 and actuate the wire-twisting mechanism, after 40 which a further movement of the slide and the rod 43 only maintains the tip of the latter in a position in which it prevents a repeating of the wire twisting and wire cutting operation. As soon as this twisting and cutting has occurred, which is easily judged from the click of the clutch part of the mechanism, the operator releases his pressure on the main treadle 30, thereby swinging 45 the friction drive parts out of operative relation and permitting the spring 22 to return the clamp 13 and the chain to their initial positions. The operator then presses the knob 56 and depresses the stripper treadle 52, thereby raising the banded box out of its former position and permitting the latter to be freely handled without danger of entangling the wire with any portion of the mechanism. To prevent an excessive 50 movement of the chain 16 in case of a break-

ing of the wire or the like, I preferably make the friction surface 24 in the form of an incomplete ring, thus providing a gap as shown in Figs. 2 and 5 within which gap the friction wheel 25 may freely revolve if 70 the drum has been rotated to such an unusual extent as to reach this position.

From the above it will be evident that in operating my machine, the depressing of the single treadle 30 suffices for starting the 75 power-actuated mechanism which successively and rapidly retracts the wire to tighten the loop, stops the retracting when the desired tension has been reached (as determined by the pressure of the spring 19), 80 starts the wire intertwisting and wire cutting mechanism (including cutters operating through slots in the table 1, substantially as in the said McChesney applications, but not shown in the present drawings), and 85 then guards the various parts against damage by excessive or prematurely repeated movement. Likewise, the substitution of the spring-pressed arms 11 for the rigid stops formerly used in such machines permits the 90 object to move during the banding, thus laterally equalizing the movement and stretching of the wire just as if the clamps gripping the ends of the wire loop had been correspondingly spread during the said tightening of the loop. In this way, I not only 95 secure a more uniform tension in the different parts of the loop, but also equalize the extent to which the wire indents the several edges of the package, such as the four edges 100 of an ordinary box. Thus, instead of having the indenting quite deep at one edge (as was likely to be the case with the older method) I have been able to reduce this indenting to such an extent that I can tightly 105 band even frail paper boxes or paper covered packages of currency without unduly indenting the covering in either case.

However, it should be understood that the drawings and description only disclose an 110 illustrative embodiment of my invention, and that I do not wish to be limited to the particular details of construction or arrangement therein disclosed, it being obvious that the same might be varied in many ways without departing from the spirit of the appended claims.

I claim as my invention:

1. In an appliance for banding an object with a wire loop encircling the same, two 115 grippers disposed for gripping portions of the wire spaced by the wire forming the loop, means for relatively moving the grippers, and a yielding stop engaging the object to resist a movement of the latter during the 120 relative moving of the grippers.

2. In an appliance for banding an object with a loop of wire encircling the object and presenting end portions extending in opposite directions, grips respectively clamping 125 130

- the said wire ends adjacent to a single face of the object, means for relatively moving the grips to tighten the loop around the object, and a stop engaging the object and resisting the movement of the object toward one of the grips during the said tightening. 3. In an appliance for banding an object with a loop of wire encircling the object and presenting end portions extending in opposite directions, grips respectively clamping said wire ends, means for relatively moving the grips to tighten the loop around the object, and a stop engaging the object and resisting the movement of the object toward one of the grips during the said tightening, the stop being yieldingly arranged to permit a limited movement of the object toward the last named grip during the said tightening.
- 10 4. In an appliance for banding an object with a loop of wire encircling the object and presenting end portions extending in opposite directions, grips respectively clamping said wire ends, means for relatively moving the grips to tighten the loop around the object, a stop engaging the object and resisting the movement of the object toward one of the grips during the said tightening, the stop being yieldingly arranged to permit a limited movement of the object toward the last named grip during the said tightening; and means for regulating the resistance offered by the stop to the moving of the object.
- 15 5. In an appliance for banding an object with a wire loop encircling the object, a support for the object, grips carried by the support and engaging substantially end portions of the wire loop, and coöperating means carried by the support for moving the grips farther apart and for moving the object with respect to the support to maintain the object substantially medial with respect to the grips.
- 20 6. In an appliance for banding an object with an encircling loop of wire, a support for the object, a pair of grips respectively engaging end portions of the wire loop, one of the said grips being fast upon the support and the other movable with respect thereto, means for moving the latter grip to tighten the loop, and yielding stop means upon the support engaging the object to resist a movement of the object in the same direction with the last named grip.
- 25 7. In an appliance for banding an object with an encircling loop of wire, a support for the object, a pair of grips respectively engaging end portions of the wire loop, one of the said grips being fast upon the support and the other movable with respect thereto, means for moving the latter grip to tighten the loop, and yielding stop means upon the support engaging the object to resist a movement of the object in the same direction with the last named grip in combi-
- nation with means for regulating the resistance of the stop means to the said movement of the object.
8. In an appliance for banding an object with a wire loop encircling the object, separate grippers for gripping two portions of the wire, means for relatively moving the grippers, and means responsive to the operation of the last named means for causing the object to move substantially half as far as the grippers are relatively moved.
- 70 9. In a wire-banding appliance, a support for an object, grips carried by the support and respectively disposed for engaging the ends of a wire loop encircling the object; means carried by the support for relatively moving the grips and thereby tightening the loop about the object, and means carried by the support and responsive to the moving of the grips for maintaining the object substantially stationary with respect to the support.
- 80 10. In wire tensioning means for an appliance of the class described, a flexible element connected to the wire, a drum around which the flexible element may be wound, an incomplete friction ring on a face of the drum, a continuously rotating friction wheel disposed near the friction ring, means for normally holding said wheel out of contact with said ring, and means for forcing the wheel against the ring.
- 85 11. Wire tensioning means for a wire tying appliance, including a clamp for gripping the wire, a flexible member fastened at one end to the clamp, pull means fastened to the other end of the flexible member and arranged for pulling said member to cause the clamp to tension the wire, the flexible member being disposed in angular formation, a movable guide for said member disposed at the apex of the said angle, and yielding means pressing said guide away from said clamp.
- 90 12. Wire tensioning means for a wire tying appliance, including a clamp for gripping the wire, a flexible member fastened at one end to the clamp, pull means fastened to the other end of the flexible member and arranged for pulling said member to cause the clamp to tension the wire, means for limiting the action of the pull means to that producing a predetermined tension on the wire, and means for automatically returning the clamp to its starting position.
- 100 13. In wire tensioning means for an appliance of the class described, a flexible band connected to the wire, a drum to wrap the band about the same around which one end of the band may be wrapped, power means for rotating the drum, means for limiting the rotation of the drum by the power means, and means for rotating the drum back to its initial position.
- 115 14. In wire tensioning means for an ap-
- 120
- 125

pliance of the class described, a flexible band connected to the wire, a drum around which one end of the band may be wrapped, power means for rotating the drum, means for limiting the rotation of the drum by the power means, and common means for returning the band and drum to their starting positions.

15. In a wire tying appliance, a table, means on the table for holding an object 10 and for gripping both ends of a wire loop encircling the object, power means for separating the two wire gripping means and thereby tensioning the said loop, and a spring-pressed slide carried by the table and arranged for limiting the separational 15 movement imparted to the wire gripping means by the power means.

16. In a wire-tying appliance, means for holding portions of a wire loop overlapped, 20 means for tensioning the loop, and means responsive to a predetermined tensioning of the loop for intertwisting the overlapped loop portions; the aforesaid means including a continuously operating power element, 25 trip means for connecting said element with the wire intertwisting means, release means for disconnecting the last named two portions of the mechanism, and an operating member responsive to the tensioning of the 30 loop and arranged both for actuating the trip means and for thereafter latching the trip means in inoperative position.

17. In a wire-tying appliance, means for holding portions of a wire loop overlapped, 35 means for tensioning the loop, and means responsive to a predetermined tensioning of the loop for intertwisting the overlapped loop portions; the aforesaid means including a continuously operating power element, 40 trip means for connecting said element with the wire intertwisting means, release means for disconnecting the last named two portions of the mechanism, and an operating member responsive to the tensioning of the 45 loop and arranged both for actuating the trip means and for thereafter latching the trip means in inoperative position, in combination with cooperating means for discontinuing the wire tensioning portion of 50 the mechanism and for retracting the said operating member.

18. In wire twisting mechanism, a continuously rotating member, wire twisting means including a rotatable element, a 55 clutch for connecting said member and element, trip means for setting the clutch, release means for throwing the clutch out after a predetermined rotational movement of the rotatable element, and an operating 60 element arranged for actuating the trip means and for thereafter latching the trip means in inoperative position to prevent its repeating the setting of the clutch.

19. Mechanism as per claim 18, including 65 as part of the trip means an element nor-

mally in the path of the operating element but moved out of said path by the engagement of a clutch portion thereagainst.

20. In a machine of the class designated, wire tensioning means including a flexible 70 member arranged for tensioning the wire by a movement of the said member in one direction, means for moving the flexible member in the said direction, an idler over which the flexible member passes, a movable 75 mounting for the idler, and yielding means resisting the movement of the said mounting.

21. Wire tensioning means including a flexible member arranged for tensioning the 80 wire by a movement of the said member in one direction, an idler over which the flexible member passes, a slidable mounting for the idler, and yielding means resisting a sliding movement of the said mounting. 85

22. Wire tensioning means including a flexible member arranged for tensioning the wire by a movement of the said member in one direction, an idler over which the flexible member passes, a slidable mounting for 90 the idler, power means for moving the flexible member in the said direction, yielding means arranged for resisting a movement of the slidable mounting of the idler until the wire has been tensioned to a predetermined extent, and means actuated by a movement of the said slidable mounting for operatively disconnecting the said power means. 95

23. In an appliance for banding an object 100 with a wire loop encircling the object, a support for the object, grips carried by the support and engaging substantially end portions of the wire loop, and coöperating means carried by the support for moving 105 the grips farther apart and for maintaining the object substantially medial with respect to the grips, and means for securing portions of the wire loop to each other while the object is thus medially maintained. 110

24. In an appliance for banding an object with a wire loop encircling the object and initially presenting portions longitudinally overlapping each other, grips for gripping the wire at points on opposite sides of the 115 said overlapping, means for imparting separatory movement to the grips, and means for disturbing the resulting tensioning substantially equally in opposite directions from the said overlapping. 120

25. In an appliance for banding an object with a wire loop encircling the object and initially presenting portions longitudinally overlapping each other, grips for gripping the wire at points on opposite sides of the 125 said overlapping, means for imparting separatory movement to the grips, means for distributing the resulting tensioning substantially equally in opposite directions from the said overlapping, and means for 130

thereafter securing overlapping portions of the wire to each other.

26. Grips engaging portions of a wire loop encircling an object, and relatively responsive means for moving the grips farther apart and for maintaining a given part of the object substantially medial with respect to the grips.

27. Grips engaging portions of a wire loop encircling an object, relatively responsive means for moving the grips farther apart and for maintaining a given part of the object substantially medial with respect to the grips, and means for limiting the movement of the object with respect to one of the grips.

28. In a package-banding machine, a support for a package, a stripper for raising the package off the support, means for actuating the stripper, and yielding means normally holding the actuating means out of operative relation to the stripper.

29. In a package-banding machine, a support for a package, a stripper for raising the package off the support, lever-operated

means for raising the stripper; and yielding means controlled by the operator separately from the lever-operated means and normally holding the latter out of operative relation to the stripper.

30

30. In a package-banding machine, a support for a package, band closing mechanism carried by the support; a stripper carried by the support and movable with respect thereto to move the package clear of the said mechanism, actuating mechanism for causing the stripper to effect the said movement of the package, and means controlled by the operator for normally holding the actuating mechanism out of operative relation to the 40 stripper.

35

31. In the wire-banding of an object, the method of securing an even tensioning of the wire about the object, which consists in yieldingly opposing a movement of the object toward the direction from which the wire is being tensioned.

45

Signed at Chicago, Illinois, September 29th, 1917.

ARTHUR G. GUENTHER.
